CLEAT

Alexander A. McDonald, Quincy, Mass.

Application November 24, 1936, Serial No. 112,571

3 Claims. (Cl. 114—218)

This invention relates to improvements in cleats of the type utilized for securing ropes or other like load-sustaining lines.

Primarily, the object of the invention is to provide a cleat to which a rope or the like can be secured with a minimum effort and can also be quickly released.

A further object of the invention is to provide a cleat comprising a post around which the 10 rope is wound and means which will permit the rope to be firmly secured after the placement of a single convolution of the rope around said post.

Another object of the invention is to provide a cleat to which the single convolution of rope 15 can be secured by the provision of means which cannot possibly become inoperative and which will preclude misplacement of the so-called hauling end of the rope.

More specifically, the invention contemplates 20 a cleat formed of a base having a post provided, preferably, with oppositely extending arms forming in conjunction with the base recesses gradually tapering toward the post. The base is also formed with an opening through which the hauling 25 end of the rope extends and said opening is so located with respect to one of the arms as to position a portion of the rope beneath said arm so that when a single convolution of the rope is wrapped around the post, it can be wedged 30 between the said portion of rope and said arm by pulling in one direction on the free end of the rope, the yielding character of the rope increasing the wedging action. Likewise, to release the 35 rope the free end thereof need only be pulled in the opposite direction. In other words, no mechanical devices that might jam or become broken or otherwise inoperative are utilized but, nevertheless, the rope can be quickly and firmly secured on the cleat after a single convolution 40 is laid around the post and, by the same token, can be quickly released.

With these and other objects in view, the invention consists in certain details of construction and combinations and arrangements of 45 parts, all as will hereinafter be more fully described and the novel features thereof particularly pointed out in the appended claims.

In the accompanying drawing—

Figure 1 is a plan view of a cleat embodying 50 the present invention, the cleat illustrated in this instance being known as a swinging cleat;

Fig. 2 is a side elevation of the cleat disclosed in Fig. 1, the rope being shown attached to the cleat;

Fig. 3 is a similar view with the rope removed;

Fig. 4 is a transverse vertical section on the line 4—4 of Fig. 3;

Fig. 5 is a top plan view of a cleat adapted to be fixed to a supporting surface; and

Fig. 6 is a side elevation of the cleat illustrated in Fig. 5.

The so-called swinging type of cleat illustrated in Figs. 1 to 4, is especially adapted for use aboard sailing vessels, particularly yachts, in connection with handling of the sails and rigging. It is referred to as a swinging cleat because instead of being fixedly attached to a supporting surface, it is merely attached at one end to the securing rope, as indicated at 10, which, in turn, is secured to a structural part of the vessel 10 (not shown), so that the cleat is free to swing with the load-sustaining or hauling rope 11. The rope 10 is looped through an eye 12 at one end of the base 13 of the cleat and one end of the load line or hauling rope 11 is secured in an 20 eye 14 at the opposite end of the base.

Intermediate the eyes 12 and 14, the base is provided with a post 15 around which the free end of the rope 11 is adapted to be wound, the convolution of the rope being retained on the post 25 by one or more arms 16, 17, formed at the upper end of the post and extending in opposite directions over the base. Preferably, the under surfaces of the arms 16, 17, are inclined, as shown, so that said arms, in conjunction with the base, 30 form gradually tapering recesses in which the convolution of rope is received.

In accordance with the present invention, the base of the cleat is also formed with an opening 18 through which the free end of the load 35 line or rope 12 freely passes, as shown in Figs. 1 and 2. This opening 18 is so located with respect to the arm 16 that the portion of the rope extending from the opening to the post, said portion being indicated at 19, is caused to occupy 40 a position partially beneath said arm. With this arrangement, when the hauling end of the rope has been drawn taut, and a convolution of rope 45 is laid around the post, the rope can be firmly secured on the cleat by simply pulling on the free end of said rope to wedge the convolution between the arm 16 and the underlying portion 19 of the rope. The resiliency of the rope facilitates and increases this wedging action and it will be found that the rope can be securely held 50 on the cleat even though only a single convolution is laid around the post. This, of course, minimizes the time required for securing the rope on the cleat. Likewise, the rope can be quickly released and removed from the post. It 55

is only necessary to pull the free end of the rope with a more or less snap action in the opposite direction or away from the post toward the opening 18. This will dislodge the wedged 5 portion of the rope and permit its removal from the post, if complete removal thereof is desired. Not only is the time element important and one of the advantages of the present cleat but it will be apparent that no mechanical attachments, apt 10 to become jammed or otherwise rendered inoperative, are involved. Also, the so-called hauling portion of the rope is not likely to be misplaced due to its being threaded through opening 18.

In the fixed type of cleat shown in Figs. 5 15 and 6, the base 13 is made deeper and hollow and the opening 18 is formed in an extension 20 formed at one end of said base at a point where it will be spaced from the supporting surface on which the cleat is secured. Openings 21 are 20 formed in the base to accommodate suitable fastening elements by which the cleat is fixedly secured to its supporting surface. This fixed or stationary cleat is adapted for use where lead of the rope, or that end which sustains the load, 25 is always disposed in the same direction. In all other respects, the two forms of cleat function in the same manner.

It will be appreciated that the eyes 12 and 14 and opening 18 vary in size, according to the 30 cross-section or size of rope used with the cleat.

What I claim is:

1. A cleat of the character described comprising a base, a post, oppositely disposed arms on said post overhanging said base and forming with 35 the base tapering recesses in which a length of rope wrapped in a convolution around the post can be engaged, portions of the opposed surfaces of said arms and said base being spaced apart

less than twice the diameter of the rope, and means on said cleat for positioning a portion of the load sustaining end of the rope partially in the recess beneath one of said arms whereby the convolution of the rope will be yieldingly wedged between the said arm and said underlying portion of rope. 5

2. In a cleat of the character described, a base, a post, an arm on said post overhanging said base, the under surface of said arm being inclined to form in conjunction with said base a recess tapering toward the post, said recess being adapted to receive a rope laid in a convolution around the post, and means provided on said base to position that portion of said rope intermediate said means and post partially beneath said arm, the spacing of said arm and base being such that said convolution around the post will be wedged between said arm and that said portion of rope positioned partially beneath said arm. 10 15

3. In a cleat of the character described, a base, a post, and an arm on said post overhanging said base and forming in conjunction with the base a recess adapted to receive a rope laid in a convolution around said post, said base having an opening therein through which a portion of the rope is adapted to extend, said opening being so located with respect to said arm and post as to position that portion of the rope intermediate the opening and post partially beneath said arm, and the spacing of said base and overhanging arm being such that the convolution of rope around the post will be wedged between said arm and the said portion of rope positioned partially beneath the arm. 25 30 35

ALEXANDER A. McDONALD.
